US00D963681S

(12) **United States Design Patent** (10) Patent No.: **US D963,681 S**
(45) Date of Patent: **** Sep. 13, 2022**

(54) **PORTION OF A DISPLAY SCREEN WITH A GRAPHICAL USER INTERFACE**

(71) Applicant: **Hoffmann-La Roche Inc.**, Little Falls, NJ (US)

(72) Inventor: **Kevin Adam Stewart**, Dundee (GB)

(73) Assignee: **Hoffmann-La Roche Inc.**, Little Falls, NJ (US)

(**) Term: **15 Years**

(21) Appl. No.: **29/822,615**

(22) Filed: **Jan. 11, 2022**
